UNITED STATES PATENT OFFICE

172,519

BELT

Altha Maude Schick, Larkspur, Calif.

Application December 1, 1953, Serial No. 27,857

Term of patent 14 years

(Cl. D3—10)

To all whom it may concern:

Be it known that I, Altha M. Schick, a citizen of the United States of America, residing in Larkspur, California, have invented a new, original, and ornamental Design for a Belt, of which the following is a specification, reference being had to the accompanying drawing, forming a part hereof.

Fig. 1 is a top plan view of a belt showing my design;

Fig. 2 is a bottom plan view; and

Fig. 3 is a top edge view thereof.

I claim:

The ornamental design for a belt, as shown.
